Primary Examiner — Phillip S Hyder*(74) Attorney, Agent, or Firm* — Carr & Ferrell LLP**CLAIM**

The ornamental design for a cutter, as shown and described.

DESCRIPTION

FIG. 1 is a perspective view of a cutter with our new design.

FIG. 2 is a front view of the cutter of FIG. 1.

FIG. 3 is a back view of the cutter of FIG. 1.

FIG. 4 is a left side view of the cutter of FIG. 1; and,

FIG. 5 is a right side view of the cutter of FIG. 1.

The broken line depicts the boundaries of the claimed design.
